UNITED STATES PATENT OFFICE.

LEON M. FARNUM, OF LANSDOWNE, PENNSYLVANIA, ASSIGNOR TO THE S. S. WHITE DENTAL MANUFACTURING COMPANY, A CORPORATION OF PENNSYLVANIA.

ARTIFICIAL TOOTH.

Application filed November 22, 1919. Serial No. 339,818.

To all whom it may concern:

Be it known that I, LEON M. FARNUM, a citizen of the United States, and a resident of Lansdowne, in the county of Delaware, State of Pennsylvania, have invented certain new and useful Improvements in Artificial Teeth, of which the following is a specification, reference being had to the accompanying drawings.

10 My invention relates particularly to artificial teeth that are provided with means, comprising a metallic anchor, by which they may be attached to their mounting, and is especially directed to that class of artificial 15 teeth wherein an anchor of refractory metal is embedded and baked in the tooth body, and a pin of less refractory metal subsequently soldered to said anchor.

The principal objects of my invention are 20 to provide a tooth with an anchor capable of being baked therein, and so formed and constructed as to afford a highly efficient retention for the pin or other securing member, and having its retaining means so disposed and extended as to avoid visible discoloration of the tooth body.

Other objects of my invention are to provide an artificial tooth with an anchor arranged to afford easy entrance of the pin or 30 other securing member thereinto, and to produce an undercut cavity surrounding said pin for the flow of the securing medium, such as solder, which is designed to effect the union of said anchor and pin.

35 The form of my invention as hereinafter described, comprehends an artificial tooth provided with a pin-receiving cavity and having embedded therein a cup-shaped anchor comprising a base wall and conical walls diverging toward the lingual surface of the tooth body, and terminating in a radially-extending flange, said pin-receiving cavity having a transverse dimension less than the transverse dimension of the open 40 mouth of said cup-shaped anchor, for the reception of a pin to be soldered thereto.

45 My invention further includes all of the various novel features of construction and arrangement as hereinafter more definitely specified.

50 In the accompanying drawings, Figure 1 is a longitudinal sectional view of a tooth in bisected form, having embedded therein an anchor constructed in accordance with my invention; Fig. 2 is a longitudinal sectional

view of said tooth and anchor after it has been baked or fired and reduced to a porcelain state; Fig. 3 is a longitudinal sectional view of the porcelain tooth, showing the solder and pin in place to be soldered to the 60 anchor; Fig. 4 is a longitudinal sectional view of said tooth, showing the pin soldered to the anchor; Fig. 5 is a perspective view of the anchor per se; Fig. 6 is a perspective view of a convenient form of the piece of 65 solder employed to secure the pin and anchor together; Fig. 7 is a perspective view of the pin; Fig. 8 is a perspective view showing the form that the solder assumes upon being fused and cooled to effect the union between 70 the anchor and the shank of the pin; and Fig. 9 is an enlarged longitudinal sectional view showing the pin soldered to the anchor.

In said figures, the tooth body 1 is molded with the pin cavity 2, at the closed end of 75 which said tooth body is provided with the dished anchor plate 3, preferably in the form of an ordinary tin pie-plate, as shown in perspective in Fig. 5, having the base wall 4 and conical walls 5 diverging toward the 80 lingual surface of the tooth body, which terminate in the radial flange 6 extended peripherally beyond the cylindrical walls of the pin cavity 2, as best shown in Fig. 1.

The anchor plate 3 is formed of a highly 85 refractory metal such as platinum, that will withstand the high temperature necessary for fusing the porcelain body 1 of the tooth, and affords a metallic attachment to which the pin of a less refractory metal 7, comprising 90 the shank 8 and head 9, may be secured by solder 10, which may be introduced into the cavity of the anchor plate 3 preferably in the form of a disk 11, as shown in Figs. 3 and 6, so that when the pin is inserted in the 95 pin cavity 2 and the tooth heated to a temperature sufficient to melt the solder 10, said pin may be moved or forced into engagement with the base wall 4 of the anchor plate 3, thereby displacing the solder and causing it to flow into the annular space afforded by the conical walls 5 of the anchor plate 3 to effect a rigid union between the shank 8 of the pin 7 and said anchor plate 3.

100 It may be here noted that in firing or baking the bisected tooth body shown in Fig. 1 to form the fused porcelain tooth body shown in Figs. 2, 3 and 4, the shrinkage effected in the fusing operation tends to restrict the pin cavity 2, as best shown in Fig. 110

2, and thereby produce a curved shoulder 13, affording an undercut recess which is filled by the solder 10, and produces the fillet 15 between the flange 6 of the anchor plate 3 and the shank 8 of the pin 7, which materially strengthens the union between said anchor plate 3 and pin 7, thereby affording a solid head embedded within the tooth body which cannot be withdrawn therefrom.

10 It will be obvious that the inclined conical walls 5 of the anchor plate 3 afford a wide open mouth for the entrance of the shank 8 of the pin 7, so that the end of said shank 8 may not be obstructed, but may be guided by the inclined walls into a central position to its seat against the base wall 4 of the anchor plate 3.

Although I have referred to the tooth securing member as a pin, it is to be understood that it may be of any desired form and, therefore, I do not desire to limit my invention to the precise details of construction and arrangement as herein set forth, as

it is obvious that various modifications may be made therein without departing from the essential features of my invention as defined in the appended claim.

Having thus described my invention, I claim:-

An artificial tooth having a pin-receiving cavity, arranged to receive a pin inserted therein, and an anchor baked in the body of said tooth, and comprising a base wall, forming the buccal wall of said cavity, side walls extended lingually and arranged to embrace the end portion of said pin in spaced relation therewith, and terminating lingually in a flange extended laterally therefrom, and embedded in the body of said tooth.

In witness whereof, I have hereunto set my hand this 21st day of November, A. D., 1919.

LEON M. FARNUM.
